United States Patent Office

Des. 232,284

Patented Aug. 6, 1974

232,284

WINE RACK OR SIMILAR ARTICLE

Ronald Keith Shuck, 351 Dorantes Ave.,
San Francisco, Calif. 94116

Filed Mar. 16, 1973, Ser. No. 342,254

Term of patent 14 years

Int. Cl. D6—04

U.S. Cl. D6—114

FIG. 1

FIG. 3 FIG. 4

FIG. 1 is a perspective view of an embodiment of the wine rack or similar article embodying my new design;

FIG. 2 is a top plan view thereof;

FIG. 3 is a front elevation view thereof;

FIG. 4 is a side elevation view thereof.

The characteristic feature of my design resides in the specific coil-like configuration of the bottle supports as shown.

I claim:

The ornamental design for a wine rack or similar article, as shown and described.
